OTTO GUENTHER, OF ESSLINGEN, GERMANY, ASSIGNEE TO THE SUPERHEATER COMPANY, OF NEW YORK, N. Y., A CORPORATION OF DELAWARE.

METHOD AND APPARATUS FOR CONTROLLING THE FEED-WATER SUPPLY TO STEAM BOILERS.

Application filed May 29, 1923. Serial No. 642,209.

To all whom it may concern:

Be it known that I, OTTO GUENTHER, a citizen of Germany, residing at Esslingen, Wurttemberg, Germany, have invented certain new and useful Improvements in Methods and Apparatus for Controlling the Feed-Water Supply to Steam Boilers, of which the following is a specification.

This invention relates to a method of and means for supplying feed water to steam boilers.

When, in steam boilers, the feed water is delivered exclusively into the steam space, such water reaches the water space of the boiler so highly heated that the difference in temperature between the feed water and the boiler water is very slight. Since the smaller the temperature range between heating gases and water, the lower the thermal efficiency, this method of feeding is undesirable at such times at which there is a heavy demand for steam, due to prolonged power development by the engine.

When, on the other hand, the feed water is delivered exclusively into the water space of the boiler, there is danger of the production of injurious effects upon the strength and tightness of the boiler owing to the increase of difference in temperature between water and heating gases.

The object of this invention is to provide a method by which the disadvantages of either of the two systems of feeding hereinabove referred to may be minimized, and the efficiency of operation of the boiler may be increased; and also to provide apparatus by means of which said method may be carried out, either automatically or by manual control.

My improved method contemplates the introduction of the feed water to the steam space of the boiler at such times at which the demand for steam is very much diminished or absent, and its introduction to the water space, when the demand for steam is active.

My improved apparatus consists of a feed head provided with separate water outlets so arranged that when the outlet communicating with the steam space is closed, the outlet connected with the water space of the boiler is open, or the reverse.

In the drawings forming a part hereof,

Fig. 1 is an enlarged sectional detail through a feed head or housing embodying the principles of my invention; Fig. 2 is an elevation of a locomotive showing an installation of my invention thereof, and Fig. 3 is an enlarged sectional detail of the fluid pressure actuating means showing the opening position of the steam-controlled piston for delivering water to the conduit which leads to the water space of the boiler.

One form of my improved feed head is shown in the accompanying drawings, in which 1, is the general housing of the apparatus, the upper part of this housing being divided into two chambers 17 and 18, by the partition 4; the lower part of the housing 1, being formed into a single chamber 7. At 5 and 6 are two check valves, which, when seated, close the chambers 17 and 18 from the lower chamber 7. The check valve 5, when lifted, opens communication between the lower chamber 7, and the upper chamber 17, and the check valve 6, when lifted, opens communication between the lower chamber 7 and the upper chamber 18.

The upper chambers 17 and 18 are provided with openings 19 and 20, to give access to the check valves 5 and 6, these openings being closed with suitable caps when the apparatus is in service. The chamber 17 is provided with a lateral outlet 8, connecting with the steam dome of the boiler, and the chamber 18 is provided with a similar outlet 9, connecting with the water space of the boiler.

The lower chamber 7, is connected to the feed water supply by a pipe 2. To the lower chamber 7, there is attached a cylinder 16, in which is fitted a piston 12, this piston 12 being free to move axially in the cylinder 16 according to the preponderance of pressure upon its upper or lower side. The cylinder 16 is fitted with a pipe connection 3, communicating with the delivery passage of the steam beyond the control valve, for instance, with the valve chest of the locomotive engine. At 13 is a relief pipe connection, providing communication between the space above the piston 12 and the outer air. At 11, is a spindle or valve-stem by which the piston 12 is connected to the check valve 6. Slidably mounted upon

the spindle 11 is a valve 10 for closing the chamber 7 from the cylinder 16.

At 15 is a lever-arm mounted upon a stem 14, this stem 14 passing through a suitably packed opening in the wall of the chamber 7. The lever arm 15 is in engagement with the valve spindle 11, so that a movement imparted to the lever arm 15 by a torsional effort upon the stem 14, will be transmitted through the valve spindle 11, and enable the check valve 6 to be opened or closed positively from without.

The operation of such apparatus is as follows:

15 When the control valve, for instance the throttle valve of the locomotive is opened and steam is being delivered, for instance when the engine is in tractive operation, steam pressure from said passage, for 20 instance from the valve chest of the locomotive, entering the cylinder 16 by the pipe 3, forces the piston 12 upwards, this motion being transmitted to the check valve 6 by the spindle 11, lifting the check valve 6 25 from its seat and opening communication between the chamber 7 and the chamber 18, so that feed water entering by the pipe 2, will have a passage through the chamber 7, past the lifted check valve 6 to the port 30 9, and on through to the water space of the boiler.

When the control valve is closed, or steam pressure through the pipe 3 is cut off by any suitable means, check valve 6 closes, 35 because of the boiler pressure above it, and the pressure of the feed water opens the check valve 5, and passes through the chamber 17 and port 8 to the steam space of the boiler.

40 The opening and control of the check valve 6 by the action of the steam pressure in the cylinder 16, may be replaced by the operation of the valve spindle 11 by the lever arm 15 and stem 14, the latter being 45 manually controlled by the operator.

By my invention I utilize only excess steam, which might otherwise be wasted, for preheating the feed water, or, in other words, I preheat the feed water within the steam 50 space only when a suitable excess of steam is available; while, on the other hand, when there is an immediate or continuous demand for steam I introduce the feed water into the water space and thus do not diminish 55 the available supply of steam.

It should be understood that the apparatus above described is illustrative only, and that my method is not limited to the employment of such apparatus; and that many changes 60 of form and structure may be made in such apparatus, itself, without departing from the spirit of my invention as covered by the claims. For instance the outlet 8 may be connected to the water space and the outlet

9 to the steam space, when the apparatus 65 is to be manually operated.

I claim:

1. The method of supplying feed water to a steam boiler which consists in conducting the water to the boiler in two separate paths, one of which paths terminates in the steam space of the boiler and the other of which terminates in the water space of the boiler, permitting the feed water to flow through the first named path when the 75 demand for steam is substantially diminished, while preventing its flow through the other path, and permitting the flow of the feed water through said other path, while preventing its flow through the first named 80 path when the demand for steam is active.

2. In a feed water control mechanism for steam boilers the combination of a housing having an outlet for receiving a connection to the steam space of a boiler, an outlet for 85 receiving a connection to the water space of a boiler, an inlet for receiving a connection from a source of water supply, a member for controlling said first mentioned outlet, a member for closing the other outlet, and fluid pressure actuated means responsive to 90 fluctuating pressure in the steam line depending upon steam demand for directing the flow through one or the other of said outlets.

3. In a feed water control mechanism for 95 steam boilers the combination of a housing having an outlet for receiving a connection to the steam space of a boiler, an outlet for receiving a connection to the water space 100 of a boiler, an inlet for receiving a connection from a source of water supply, a member for closing said first mentioned outlet, a member for controlling the other outlet, fluid pressure actuating means responsive to 105 fluctuating pressure in the steam line depending upon steam demand for directing the flow through one or the other of said outlets, and a manually operable controlling 110 device connected with one of said closing members.

4. In the feed water control mechanism 115 for steam boilers, a feed water supply, a pair of conduits connected with said supply, one of said conduits being connected with the boiler below the water line thereof and the other of said conduits being connected to said boiler above said water line, a valve in each of said conduits and means for 120 opening the valves automatically to supply feed water through the second of said conduits when the demand for steam is substantially diminished and through the first of said conduits when the demand for steam is active.

In testimony whereof I have hereunto set 125 my hand.

OTTO GUENTHER.
